D20-24

EX

OR D 4,079

4079

PATENTED MAY 31 1870

✓
J. Winston Sneed
W. Marshall
Ira
George W. L.
John D. Lee
Nathaniel

United States Patent Office.

GEORGE W. LANGHORNE, JOHN D. LANGHORNE, AND NATHANIEL B. JOHNSTON, OF LYNCHBURG, VIRGINIA.

Design No. 4,079, dated May 31, 1870.

DESIGN FOR A TRADE-MARK.

The Schedule referred to in these Letters Patent and making part of the same

---

We, GEORGE W. LANGHORNE, JOHN D. LANGHORNE, and NATHANIEL B. JOHNSTON, partners, under the firm and style of G. W. LANGHORNE & Co., of the city of Lynchburg, county of Campbell and State of Virginia, have invented and produced a new and original Design for a Trade-Mark, of which the following is a specification.

Our design consists of a card or label having in the center the picture of a partridge standing on a stump, and above it, in letters, the words "Bob White." Beneath these, and separated from each other by the head and throat of the bird, are the words, "smoking tobacco," while the background of the card is shaded by a range of mountains, visible to right and left of the center picture. Immediately below the center picture are the words, "manufactured by G. W. Langhorne and Co., Lynchburg, Va."

Claim.

We claim as our invention—
The design for a trade-mark, as described and shown.

GEORGE W. LANGHORNE.
JOHN D. LANGHORNE.
NATHANIEL B. JOHNSTON.

Witnesses:

LOUIS L. ARMISTEAD,
JOHN WINSTON IVEY.